STOKER

Chester E. Shaffer, Arlington, N. J., assignor, by
mesne assignments, to Koppers Company, In-
corporated, Pittsburgh, Pa., a corporation of
Delaware

Application August 25, 1944, Serial No. 551,084

5 Claims. (Cl. 110—46)

1

The present invention relates, in general, to automatic heating apparatus employing solid fuels, and has reference more particularly to improvements in a stoker mechanism for automatically de-ashing the fuel bed.

The primary object of the present invention is to provide improvements for automatically de-ashing the fuel beds of domestic furnaces which are continuously fed with fuel in such manner that the fuel bed is kept substantially free of ash thereby preventing the formation of clinkers and making the fuel pieces readily available to combustion air.

Another object of the present invention is to provide a fuel stoker which will be operative for automatic removal of ash from a fuel bed.

It is a further object of the present invention to provide a simple, stationary inclined grate with means for maintaining the same at all times substantially free of ash accumulations so that the radiant heat of an incandescent fuel on the grate will be more completely and efficiently employed.

Yet another object of the present invention is to provide a fuel-bed agitating device that is operative also to feed solid fuel to a fuel bed and that is effective in agitating burning fuel, thus to shake ashes therefrom without having moving metal parts in contact with the burning fuel.

The invention has for further objects such operative advantages as may be found to obtain in the processes or apparatus hereinafter described or claimed.

In the accompanying drawings forming a part of this specification and showing for purposes of exemplification preferred apparatus and methods in which the invention may be embodied and practiced but without limiting the claimed invention specifically to such illustrative instance or instances:

Figure 1 is a diagrammatic elevational view with parts broken away, of an underfeed stoker which embodies an inverted truncated conical grate for a round boiler and a reciprocating fuel-feeding and ash-removal mechanism illustrating the preferred form of the invention.

Figure 2 is a diagrammatic plan view of the underfeed stoker mechanism shown in Figure 1;

Figure 2a is a fragmentary view showing for purpose of clarity the feed hopper and the swinging gate operating mechanism for closing the hopper;

Figure 3 is a vertical section of the inverted, conical grate taken along line III—III of Figure 1;

2

Figure 3a is a fragmentary perspective view of the mouth of the underfeed stoker showing for purpose of clarity the shape of the ledge therein illustrated.

5 Figure 4 is a plan view and Figure 5 is a side elevational view of the improved grate bar employed in the conical grate illustrated in Figures 1, 2 and 3;

10 Figures 6 and 7 are cross-sectional views of 10 the conical-grate bar taken along lines VI—VI and VII—VII of Figure 4;

15 Figure 8 is a diagrammatic elevational view in section of the automatic stoker and stationary conical grate, with parts broken away, illustrating the position of coke pieces in the apparatus when the feeder and fuel-bed agitator device is in a forward position, and when the grate is only partially full of coke;

20 Figure 9 is similar to Figure 8 and shows the 20 position of coke-pieces in the said apparatus when the said feeder and fuel-bed agitator device is in a retracted position;

25 Figure 10 is a simplified diagrammatic elevational view of a modified form of the apparatus of the present invention which is particularly adapted to use with rectangular fire pots;

Figure 11 is a diagrammatic plan view, with parts broken away of the rectangular grate and taken along line XI—XI of Figure 10;

30 Figures 12 and 13 are respectively the plan and side views of one of the side grate bars of the rectangular grate;

35 Figures 14 and 15 are respectively the plan and side views of one of the end grate bars of the rectangular grate; and

Figures 16 and 17 are respectively the plan and side views of one of the corner grate bars of the said rectangular grate.

40 The same characters of reference designate the same parts in each of the views of the drawings.

Referring more particularly to Figures 1, 2 and 2a, an automatic stoker 10 is shown in combination with a stationary inverted truncated conical

45 grate 11 that is located in the circular fire pot 12 of a boiler. Solid fuel is fed by the said stoker 10 from a bin 14 to the fuel entrance at the base of the grate 11 by means of two reciprocating plates 16 and 17, that are disposed in, respectively, stoker tube 18 and a trough-shaped covered conduit 19. The plate 17 serves to deliver the fuel from the fuel bin 14 to the tube 18 and the plate 16 delivers the fuel from plate 17 to the grate 11. The reciprocating plates are both 50 driven by a motor 20 through means comprising

a gear reducer 21, a crank 22, and a connecting rod 23 connecting the crank 22 to a driving arm 24. The said arm 24 is bolted to a heel plate 26 that is at the outer end of, and forms a part of, the reciprocating plate 16. The plates 16 and 26 move together to carry fuel delivered thereto from the plate 17, to the grate 11. The arm 24 on the heel plate 26 is also connected by a connecting link 25 with a circular drive ring 27. The drive ring 27 is connected by a rod 28 (Figs. 1 and 2a) to the outer end of plate 17. With this construction the reciprocation of the driving arm 24 will simultaneously reciprocate plates 16 and 17.

The said drive ring 27 is perforated with numerous bolt holes 29 to one of which, depending upon the angular relationship of conduit 19 to tube 18, the inner end of the rod 28 may be connected. By this arrangement the stoker may be located between a fuel bin and ash-pit doors having different angular arrangements.

The feed plate 17 conveys fuel from bin 14 to a hopper 30 which is formed by the rounded end of the conduit 19 and is set into the outer end of the stoker tube 18. The coke-pieces delivered to the hopper 30 will fall upon the conveyor feed plate 16.

The hopper 30 is provided with a swinging gate 31 that is opened on the forward stroke of the conveyor plate 17 to permit coke to pass from the conveyor plate into the hopper. To accomplish this a lug 32 that is secured to the rod 28 engages an arm 33 fixed on the pivot rod 31a of the gate 31 and opens positively the gate when the conveyor plate moves forward. A counter-weight 34 is secured to the said pivot rod 31a and moves the gate into closed position when the conveyor plate is moved rearwardly on its return stroke. As the gate 31 is opened, coke delivered by the conveyor plate 17 falls down the inclined side of hopper 30 to the heel plate 26 and conveyor plate 16. It is desirable to maintain the gate 31 closed as much as possible in order to prevent infiltration of air through the conveyor tube to the furnace. The inclined side of the hopper 30 is disposed at an angle greater than the angle of repose of coke so that no coke pieces will remain on the plate 34 to prevent the closing of the gate 31.

The coke falls through the hopper 30 and is pushed forward in the tube 18 as the plates 26 and 16 are moved in the forward stroke. On the rearward stroke of the reciprocating plate 16 the coke is held from rearward movement by a wall 35 which forms the back end of the stoker tube 18. On the front end of the feed plate 16 is mounted a pusher head 36 which has a rearwardly sloping face 38. The pusher head 36 rides on the bottom of an elbow section 39 of the stoker tube and has a substantial thickness with a recess in its upper face so that the conveyor plate is attached therein with the upper surface of the conveyor plate in the same plane as the top surface of the pusher head. The reciprocating pusher head acts positively to push the coke through the elbow of the stoker up into the fuel bed.

The construction and arrangement of the elbow section 39 form an important feature of the present invention. The front edge of the top of the stoker tube 18 projects into the throat of the elbow and forms a semi-circular projecting edge 40, as shown more particularly in the perspective view, Fig. 3a. The said projecting edge

40 of the stoker tube 18 is arcuate, or as aforesaid semi-circular, in vertical section conforming thereby to the rounded top of the tube 18 and it projects into the said throat of the stoker elbow to form a ledge which cuts off (as seen in plan view in Figures 2 and 11) the entrance into the fuel bed, so that the so-formed ledge will act as an impost temporarily to support coke arches which form at the entrance of the fuel bed. 5 When the coke is moved forwardly by the pusher head 36 and the plate 16 it moves up the circular face of the elbow and enters the fuel bed. As the coke moves upwardly in the fire pot, the projecting edge 40 tends to form arches which hold the coke against a rearward or falling movement during the forward stroke of the pusher head 36. The position of the coke at the end of the forward stroke is illustrated in Figure 8. On the rearward stroke of the pusher the support which is provided by the pusher head 36 is removed. When this support is withdrawn, coke which is held up by the projecting edge 40 suddenly falls and allows coke in the fuel bed to drop down into the elbow section 39 into the 15 position illustrated in Figure 9. This movement is important because it imparts to the coke within the fuel bed a reciprocating up and down movement across the face of the openings of the grate. Any ash that is contained in the fuel bed is worked out to the grate and the movement of the fuel insures that the ash will fall through the grate. Thus the movement of the fuel bed keeps the grate clean and the ash out 20 of the bed. 25 This action (continuous ash removal by the newly provided fuel bed movement) not only keeps the fuel bed free of ash but it provides a heat radiating surface around the fuel bed unimpaired by ash accumulation from which surface heat is radiated to the boiler walls effectively to heat the water in the boiler. The contact of hot fuel without an intervening layer of insulating ash also tends to keep the grate bars at high temperature but here their inclined disposition in close spatial relation to the water-cooled boiler walls provides for the effective cooling of the grate bars by radiation of heat therefrom to the said boiler walls.

30 Although the movement of the pusher is slow and only brings into the stoker tube 18 from three to five pieces of coke per stroke, the rearward motion of the pusher head permits a breaking of the described arch which produces an abrupt fall of the coke in the fuel bed and thus 35 provides the described fuel bed agitation.

The ash falls through the conical grate into an ashpit which is beneath and surrounds the stoker. This ash is conveyed from the pit into an ash-storage bin 42 which is located beneath 40 the stoker tube 18. The movement of the ash is carried out by means of reciprocating slats 43 that are slidably mounted in guides 44 which are positioned under the stoker elbow 39. The slats are secured to a bracket 45 which is attached to the underside of the feed plate 16. Therefore the reciprocating movement of the feed plate also effects a similar movement of the ash removal slats. Preferably an ash container would be located in the bin 42 and could be removed when it became filled with ashes.

45 The conical grate 11 which bounds the fuel bed is made up of a series of triangular shaped grate bars which are illustrated more particularly in Figures 4, 5, 6 and 7. The lower ends of the grate bars rest in a retaining ring 46 which is secured

to the upper end of the elbow section 39. The upper ends of the grate bars rest against the wall of the inner surface of the furnace. Each bar 47 is provided with six slots 48 through which the ash is removed from the fuel bed and through which air is introduced thereinto. The slots 48 are designed to provide a high ratio of open grate area to dead area and are perforated obliquely to the plane of the surface of the grate bar so that the end walls of the slots are substantially vertical when the bars are in position in the grate, thus to prevent hold-up of ash on the said end walls. Each grate bar is provided with a tapered lug 49 which fits into a corresponding opening 50 on the side of the adjacent grate bar so that the bars are locked together when they are assembled.

A modified form of apparatus forming a part of this invention is illustrated in Figures 10 to 17 inclusive. This modified form is adapted more particularly as a stoker apparatus for a rectangular boiler. The stoker and firebox differ principally in the shape of the grate and the stoker elbow which are altered to conform to the requirements of a rectangular firebox. To accomplish this three different types of grate bars are required to form the grate. Figures 12 and 13 illustrate a rectangular shaped grate-bar that is employed in positions on each side of the elongated oval-formed bottom of the grate. The positions of these grate bars are illustrated at 55, 56, 57, and 58 in Figure 11. These bars have a notched base portion 59 to rest in a supporting ring 60 that is secured to the top of the stoker elbow 61. Figures 16 and 17 illustrate a diamond shaped grate bar which is used at the corners of the rectangular firebox, such as illustrated at the points 62, 63, 64, and 65, of Figure 11. These diamond-shaped bars have a notched base 66 which rests in the supporting ring 60. At each side of the corner bars are located trapezoidal-shaped grate bars which are shown in detail in Figures 14 and 15. Two bars are required for each corner such as illustrated at 67, 68, 69, 70, 71, 72, 73 and 74 in Figure 11. The trapezoidal-shaped bars have a notched base 75 which fits into the supporting ring 60. It will be understood that all of these grate bars are provided with slots or openings to permit the movement of ash through the grate and to permit the admission of air for supporting combustion. The upper faces of these grate bars rest against the wall of the boiler, such as illustrated in Figure 10. The corner grate and the adjacent trapezoidal-shaped bars illustrated in respectively Figure 16 and Figure 14 are so designed that the angle of elevation of the grate is not materially reduced at the corners of the rectangular firebox even though a considerably longer slant height, from supporting ring to furnace wall, is there encountered.

The angle of elevation of the grate bars of the present invention, for both the rectangular and truncated-conical grates, whereby there is provided optimum conditions of combustion and radiation therefrom along with minimum accumulation of ash or production of clinker, has been found to be at least more than approximately 50° when the fuel employed is coke of customary domestic size. Variations in size of heaters and grates therefor, and in the relative size of devices of the stoker apparatus and more particularly of the said plunger head in relation of the area of the fire-bed fuel entrance will prescribe deviations in the above defined angle of elevation, which said deviation can be readily determined by sim-

ple experiment. For example, it has been found that the larger fuel entrance of the rectangular grate hereinbefore described required for continued operation without clinker formation a plunger head of increased face area. The plunger head of increased size was also found beneficial in supporting the coke arches in a stoker mouth less conducive to their formation.

It is believed from observation of stoker operation, that the angle of elevation of the grate bars must be sufficiently steep that lines of force from the moving plunger head will be directed to, and will move, the fuel pieces lying on the grate; and that this requirement will be satisfied when the angle of elevation is, within reasonable limits, the complement of the angle of repose of the employed fuel. Variation in the form, size, and relative duration of the described arch and in the resultant efficacy in ash removal of the falling of the arch of course occurs, and thus the above description is not intended to be limiting but is offered merely to augment the explanation of the action of the apparatus in providing automatic ash removal as well as automatic fuel feeding.

As used in the following claims, the term furnace is intended to include house-heaters of all types employing solid fuel.

The invention as hereinbefore set forth is embodied in particular form and manner but may be variously embodied within the scope of the claims hereinafter made.

I claim:

1. In a fuel combustion chamber, the combination of: a stationary grate having an upwardly increasing cross-sectional area determined by spaced bar-like members arranged about a central fuel opening at the base of the said grate; a protruding ledge cutting off, at the inlet end of the fuel opening, a portion of the area of the said central fuel opening; and means, including the said ledge and a reciprocating plunger device, operative automatically both to raise and sharply to drop a fuel bed in said grate, thereby causing combustion residues to travel downwardly through fuel interspaces of said fuel bed and also through the spaces between said bar-like members.

2. In a fuel combustion chamber, the combination of: a stationary grate having an upwardly increasing cross-sectional area determined by spaced bar-like members that are disposed about a central fuel-opening at the base of the said grate; a reciprocatory plunger which, by intermittently coming into contact with, and shortly thereafter leaving the contact of fuel lying at the entrance to the said fuel-opening and beneath fuel in a fuel bed in said grate, is operative to agitate the said fuel bed; and a protruding ledge extending across an arc of the ring about the said central fuel-opening at the fuel-inlet end thereof, and acting as an impost for momentary support of arches of fuel formed in the said opening.

3. Apparatus for automatic heating with solid fuel, said apparatus comprising the combination of: an underfeed stoker having a reciprocatory plunger that is operative both to push fuel into the fuel bed and to raise and release in successive operation a fuel bed of the so-fed fuel; an inclined, stationary grate having an upwardly increasing horizontal cross-sectional area determined by bar-like members that are disposed about a central fuel opening at the base of the said grate and that are inclined at an angle of elevation equal to at least about fifty degrees;

and a projecting ledge that extends horizontally from an arc-portion of the ring about the said central fuel opening, cuts off, a minor portion of the area of the said opening and acts in cooperation with the said plunger when the same is in forward position as an impost momentarily to support arches of the said fuel formed in the said opening, but is ineffectual to support such arches when the said plunger is in retracted position, whereby the said arches fall and the fuel bed is sharply agitated.

4. Apparatus as claimed in claim 3 wherein the shape of the said stationary grate conforms to an inverted truncated cone.

5. In a fuel combustion chamber, the combination of: a grate having an upwardly increasing cross-sectional area determined by spaced bar-like members arranged about a central fuel opening at the base of the said grate; a protruding ledge cutting off, at the inlet end of the fuel opening, a portion of the area of the said central fuel opening; a feed plunger and means to reciprocate the plunger to force fuel above the

5 said ledge and to raise and sharply to drop a fuel bed in said grate, thereby causing combustion residues to travel downwardly through fuel interspaces of said fuel bed and also through the spaces between said bar-like members.
